UNITED STATES PATENT OFFICE.

EMMET QUEEN, OF JOHNSTOWN, PENNSYLVANIA.

DRILL-JAR.

SPECIFICATION forming part of Letters Patent No. 315,547, dated April 14, 1885.

Application filed January 7, 1885. (No model.)

To all whom it may concern:

Be it known that I, EMMET QUEEN, a citizen of the United States of America, residing at Johnstown, in the county of Cambria and State of Pennsylvania, have invented certain new and useful Improvements in Drill-Jars; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to certain improvements, as hereinafter described and claimed, in drill-jars for jarring loose the drilling-tools employed in drilling wells, shafts, and the like.

Heretofore drill-jars have been constructed, some with a vertically-slotted barrel or tube, in the slots of which pins on a cylindrical piston-head slide, while others have had the piston-head formed with flat sides and ends, and still others with the piston-rod extended below the bottom of the piston-head, and the barrel provided with a central socket to receive the lower end of the piston-rod.

In constructing my drill-jar I form the cylinder or barrel with inside walls of circular or elliptical shape in cross-section, and with diametrically-opposite vertical slots, and the piston-head or plunger elliptical or oval in cross-section, and with sidewise-projecting wings, whereby the friction between the piston-head and barrel is reduced to a minimum, an easy reciprocation of the piston and piston-head is assured, the choking and binding of the parts prevented, and the loosening or breaking of the guiding devices prevented.

In the accompanying drawings, Figure 1 represents a vertical elevation, partly in section, of one of my improved jars. Fig. 2 is a vertical elevation thereof. Fig. 3 represents a transverse section on the line 2 2 of Fig. 2, and Fig. 4 represents a perspective view of the piston-head and a portion of the piston.

The several devices to which drill-jars are connected for boring the wells and operating the boring-tools and the piston of the jar are so well known that I have not deemed it nec-

essary to show them in the drawings, as they constitute no part of my present invention.

A represents the cylinder or barrel of my improved drill-jar, which is made of heavy wrought-iron or other tubing, of less diameter than the bore of the well, so that it will move freely therein, said cylinder being formed in two parts longitudinally, to permit of the plunger and plunger-head being placed in position or removed therefrom, when desired, said parts being bolted or otherwise secured together.

B represents a socket formed in the solid lower end, C, of the barrel, to which is connected the auger or drill stem. In lieu thereof, however, a ring or a plug having a socket, as B, therein may be connected to the lower end, either by screw-threads formed in the end of the tube and on the plug or other means. The bottom of the cylinder is solid, as shown, to form an anvil to receive the impact of the bottom of the plunger-head. The upper end of the cylinder A is either re-enforced or formed of increased thickness to provide a bearing or bushing, D, for the piston-rod in its reciprocating movements; or a screw or other plug having a central bore may be inserted within the upper end of the cylinder A, for the purpose of affording a bearing for the plunger and a stop for the plunger-head. The side walls of the barrel A are elliptical in cross-section, and have formed therein, in diametrically-opposite positions, vertical slots E.

F represents the piston, which may be of any suitable shape—cylindrical being preferred—and is at its upper end adapted to be connected to a sinker-bar or other device for operating the same.

G represents the piston or plunger head, which is formed integral with or separate from and welded, swaged, or otherwise attached to the lower end of the plunger-rod F. This head is, as shown in the drawings, formed of elliptical or oval shape in cross-section, with the wings or edges H thereof extending so as to enter and rest within the vertical slots E in the barrel or tube A. The width of the elliptical-shaped head at its center about equals the width of the circular or elliptical bore of the tube A, so that it may reciprocate snugly therein, and prevent dirt getting between the respective faces of the head and tube and im-

peding the movement of said head. The piston F and head G are formed of either cast or wrought metal, as preferred.

By forming the head of elliptical or oval shape in cross-section the objection heretofore existing where guide-pins are used of such pins becoming loose after some use, owing to frequent jarring, is avoided. Furthermore, the head has a smooth yet effective bearing over the entire area of each side, which insures a larger wearing-surface and a greater steadiness and easiness of movement than where the head has a flat or round face or faces, and the wings or the edges entering the slots not only prevent the head and plunger turning in the tube A, but close the slots to the entrance of foreign matter to a greater degree than will be the case where pins are used.

The working heads of jars as now constructed wear fast, and sometimes become battered, causing them to stick or bind within the tube A and require chipping. My plunger-head, being elliptical and having the

greatest amount of wearing-surface, is free from these objections, and as it wears will also wear away the sides of the slots, thus preventing the binding therein, and insuring a uniformity of bearing-surface at all times.

Having thus described my invention, what I claim is—

1. A drill-jar having an elliptical or oval-shaped plunger-head, substantially as and for the purpose set forth.

2. A drill-jar having a vertically-slotted tube, A, and a plunger adapted to reciprocate vertically within said tube, and having a plunger-head elliptical in cross-section, adapted to rest and slide within said tube A and the slots therein, substantially as and for the purpose set forth.

In testimony whereof I affix my signature in presence of two witnesses.

EMMET QUEEN.
